UNITED STATES PATENT OFFICE

2,517,983

LOOP BRIDGING STRUCTURE FOR CONVEYERS

Edward Milner Crosland, Culcheth, near Warrington, England, assignor to T. & T. Vicars Limited, Newton-le-Willows, England, a British company

Application February 13, 1948, Serial No. 3,226
In Great Britain August 28, 1940

Section 1, Public Law 690, August 8, 1946
Patent expires August 28, 1960

2 Claims. (Cl. 198—30)

1

The present invention relates to improvements in the picking up and packing of flat articles such as finished biscuits.

Biscuits are baked flat on either trays or bands, and to assist in the picking up of these biscuits so that they may be put into containers it is customary to use a stacking machine.

This machine takes the flat biscuits and puts them on edge in close formation and conveys them along a table between guides, so that it is easy for a quantity of biscuits to be picked up at a time ready to go directly into tins or trays. It is necessary to have guides or fences between the rows of biscuits so as to keep them from moving sideways, whilst as the biscuits passing over the conveyor may differ in shape and size, such guide fences must be adjustable with regard to the spacing across the conveyor. Again, as biscuits cut with the same cutter may vary slightly according to baking conditions, it is desirable that adjustment of the fence spacing may be made quickly and easily whilst the conveyor is running.

The improvements of this invention are particularly directed to this guide and means for holding the same.

The packing table is usually of considerable length, longer than it is convenient to construct an individual guide member, and it has been customary to hold these guide members, longitudinally at definite intervals, as for instance, a packing table 18' 10" long would have about three supports for these guides.

Further, the packing table is usually in the form of an endless web carrying the biscuits along, the web being run at such a speed that it will accept the biscuits that are fed to it at such a rate that a column of biscuits will remain in a substantially vertical position.

It has been usual to supply bridges over the top of the guides from which communicating pieces are hung down to support the guides, the bridge pieces being high enough up to allow the biscuits to pass underneath. However, these bridge pieces are inconvenient inasmuch as the biscuits cannot be picked up from underneath them, and at the same time biscuits that may not be in perfect formation and that lie at an angle may catch the communicating link between the bridge and the guide and so cause a stoppage in the column of advancing biscuits, which may cause breakages. Also, it has been customary to have the fences attached to the bridge pieces at fixed centres, these not being adjustable whilst the machine is running.

2

An object of this invention is to eliminate the overhead bridge pieces so that the packing table is quite clear from one end to the other, and a further object is to make the fences readily adjustable in their distance apart across the conveyor and so that the adjustment can be made whilst the conveyor is running.

According to this invention the carrying web on the packing table is looped at intervals, leaving a small space between the loops, whereby a series of slippers can be introduced which will allow the biscuits to slide across and which will at the same time provide a support for the fences. These supports may be at fixed centres, but preferably they have some adjustment across the packing table so as to more readily accommodate the varying size of biscuit that may be dealt with.

The invention is more particularly described with reference to the accompanying drawings, in which—

Figure 1 is a diagrammatic elevation of one form of conveyor,

Figure 2 is an elevational view on an enlarged scale of a loop in the conveyor,

Figure 3 is a section on the line B—B of Figure 1 showing adjustment means for the guides,

Figure 4 is an outside elevation corresponding in part to Figure 3, showing the guides in a different position of adjustment,

Figure 5 is a view of the guides detached in elevation,

Figure 6 is a corresponding plan view,

Figure 7 is a view corresponding to Figure 2 showing a modified form of construction,

Figure 8 is a sectional elevation on the line C—C of Figure 7.

A conveyor web 1, Figures 1 and 2, for conveying articles such as biscuits, may be of any desired form, but will usually be made of endless wire coils. At spaced points in its run it is looped over guide rollers 2, 3, and a larger roller 4.

The intervening space between the loops at the level of the conveyor is bridged by means of a slipper 5. Guide bars 6, 7, for the biscuits or the like articles are preferably provided with inter-engaging means at their ends, and means to lock with an upstanding projection 8 on the bridge slipper 5.

The guide bar 6 has a narrow slot 9 milled in it and is provided at its end with a tongue 11 so that it may be locked over the projection 8 and thus prevented from moving longitudinally with the conveyor. By this means also, it will be prevented from being displaced laterally. The next

succeeding guide bar 7 is also provided with a cut-away portion or slot 10 engaging over the tongue 11 so that this end of the next guide bar is also prevented from sideways displacement except with the slipper 5.

The slipper 5 is integral with or mounted on a block 12 which is preferably internally threaded to be engaged by a threaded bush 13 having a rectangular or other non-circular hole in it engaging with a key or tommy bar 14 by which the sleeve 13 can be turned, but allowing free axial displacement of the block 12 along this bar 14.

As will be seen by comparison of Figures 3 and 4, by rotating the tommy bar 14 the sleeves 13 are rotated to cause axial relative displacement of sleeves 13 and blocks 12.

A spring or weight may be provided to keep the various blocks 12 in abutting relationship one with the other. Alternatively, as shown in Figure 8, the threaded sleeve 13 may have a flange 21 at its end engaged by a fork 20 on the next block 18 so that in this case, springs or weights will not be necessary to maintain the adjusted relative displacement of the guide bars 6 as set by rotating the tommy bar 14.

Preferably the blocks 12, 18, are provided with angle plates 16, 17, overlapping with thin slipper plates 15 on the blocks.

I declare that what I claim is:

1. A conveyor for small articles comprising in combination a conveyor web, means to displace said conveyor web continuously in one direction,

means to form loops in said web at spaced intervals, bridging slippers in the gaps formed by said loops, a plurality of rectangular guide bars, notched to interengage at their ends and mounted on said slippers, and an upstanding projection on said slippers to prevent the lateral displacement of the guide bars relatively to said slippers.

2. A conveyor for small articles comprising in combination a conveyor web, means to displace said conveyor web continuously in one direction, means to form loops in said web at spaced intervals, bridging slippers in the gaps formed by said loops, guide bars on said bridging slippers, threaded bushes carrying said slippers, and a threaded key bar engaging with said bushes for axially adjusting the slippers relatively to said conveyor.

EDWARD MILNER CROSLAND.
